SHOE BOTTOM IRONING MACHINE

Charles F. Pym, Beverly, Mass., assignor to
United Shoe Machinery Corporation, Paterson,
N. J., a corporation of New Jersey

Application September 8, 1933, Serial No. 688,630
In Germany September 20, 1932

73 Claims. (Cl. 12—51)

This invention relates to machines for ironing the bottoms of shoes, and more particularly, in various important aspects, to means for ironing the marginal portion of upper materials (hereinafter referred to inclusively as the upper) before the outsole is applied to the shoe. In some aspects also the invention has more particular reference to ironing means for use in the manufacture of shoes in which the upper is secured to 10 the insole by an adhesive, and it may be also in which the outsole is thereafter secured adhesively on the shoe bottom, although it is to be understood that the invention is not thus limited in its applicability. The invention is illustrated herein as embodied in a machine of the type disclosed in United States Letters Patent No. 1,951,373, granted March 20, 1934, upon an application filed in my name, but it is to be understood that the invention is not limited to machines of 20 that type.

In the illustrated machine there is provided, in accordance with a feature of the invention, a novel construction and arrangement of means for ironing the marginal portion of an upper previously laid inwardly over an insole substantially in lasted position, along the sides of the shoe in locations between the toe and heel-end portions of the shoe and also around both ends of the shoe, although it is to be understood that the invention is not limited to means for thus ironing the upper at both ends of the shoe. In the construction shown the ironing means comprises side-ironing members extending along the opposite sides of the shoe in locations between its toe and heel end portions, end-ironing members mounted for swinging movements laterally of the shoe each about an axis substantially midway between the opposite sides of the shoe, and other ironing members extending between the end members and the side members, the several members being heated and arranged to support a shoe placed thereon bottom downward. As illustrated, the end members are movable lengthwise of the shoe and the side members laterally of the shoe in wiping engagement with the upper in response to pressure of the shoe upon them, through the action of pairs of parallel links of equal lengths which are effective, as the pressure is applied, to move the members inwardly over the shoe bottom without varying their relative positions heightwise of the shoe. Spring means is further provided for yieldingly opposing the inward movements of the several members and for progressively increasing the pressure of the members on the upper during their inward movements, the

pressure of the members being further increased after they have completed their inward movements. In accordance with a further feature, a novel construction is provided whereby the swinging or closing movements of the end members laterally of the shoe are effected by the side members. As illustrated, there are utilized for this purpose the above-mentioned ironing members that extend between the end and side members, these ironing members receiving their operative movements from the end and side members.

In the illustrated machine there is provided, as in the machine of the above-mentioned Letters Patent, means for preventing outward return movement of the side-ironing means or members until after the shoe has been substantially released from pressure, so as to avoid any possibility of displacement of the margin of the upper by outward drag of the members thereon. In order to prevent outward movement of the end-ironing means in advance of the side-ironing means there is provided, in accordance with a further feature of the invention, novel means arranged to permit the end-ironing means to move outwardly only with the side-ironing means.

It is contemplated that such ironing means may be used with substantial advantages in operating upon shoes the opposite sides of which have been previously lasted, for example by use of a machine of the character disclosed in United States Letters Patent No. 1,943,344, granted January 16, 1934, upon an application filed in my name, and in which the uppers are held in lasted position by an adhesive which has hardened or set sufficiently to prevent any loss of lasting tension, and yet is more or less yieldable under the application of heavy pressure. By the ironing means described the marginal portion of the upper is flattened against the insole and smoothed free from wrinkles by the inwardly moving heated members, which may also draw it more tightly inward over the insole. The application of increased pressure and heat to the margin of the upper at the completion of the ironing operation also tends to set the margin of the upper in its ironed-out condition so that when the shoe is finally released from pressure it will be provided with a bottom surface best fitted for the reception of its outsole. In operating on shoes of that type in which the outsole is secured by an adhesive it is further contemplated that the several ironing members may be provided with serrated upper-engaging faces

so that by their pressure on the margin of the upper, and especially the final pressure after the completion of their inward movements, they will produce a large number of indentations in the 5 surface of the upper to facilitate the roughening of the upper to receive cement for the attachment of the outsole, and in this aspect of the invention there is to be recognized a novel method as well as novel means. It is further to be 10 understood that in the novel construction and arrangement of wiping means, the invention, in various novel aspects, is not limited to use on shoes in which the marginal portion of the upper has been previously laid inwardly over an insole. 15 The above and other features of the invention, including novel means for adjusting the ironing members and various novel details of construction and combinations of parts, will now be more particularly described by reference to the accompanying drawings and pointed out in the claims. 20

In the drawings,

Fig. 1 is a view in front elevation of the upper right-hand portion of a machine in which the invention is embodied;

25 Fig. 2 is a plan view of the shoe-ironing members and the parts associated therewith;

Fig. 3 is a section on the line III—III of Fig. 1 showing the parts in their initial positions;

Fig. 4 is a section on the line IV—IV of Fig. 2;

30 Fig. 5 is a plan view of the toe-end-ironing members, illustrating diagrammatically the initial relation of the members to the toe end of a shoe;

Fig. 6 is a view similar to Fig. 5, but showing 35 the positions of the ironing members at the completion of their inward movements;

Fig. 7 is a section on the line VII—VII of Fig. 6;

Fig. 8 is a perspective view illustrating the condition of the bottom of a shoe after it has been 40 operated upon by the machine; and

Fig. 9 is a detail plan view showing ironing members having serrated upper-engaging faces.

This invention is illustrated as applied to a machine organization which is in many respects 45 similar to that illustrated in Letters Patent of the United States No. 1,549,243, granted on August 11, 1925, upon an application of E. E. Winkley, with portions of the machine constructed as disclosed in Letters Patent No. 1,951,373 above mentioned, although it is to be understood that the invention is not limited to organizations of that 50 particular character. Machines of the type illustrated in said Letters Patent No. 1,549,243 are twin machines comprising two sets of mechanisms 55 whereby one shoe is subjected to pressure simultaneously with the release from pressure of another shoe previously operated upon. Only one of the two sets of mechanisms is herein illustrated or need be referred to for an understanding 60 of the present invention. As more fully illustrated in the above-mentioned Letters Patent No. 1,549,243, the machine is provided with a pair of vertical rods 20, one of which is shown in Fig. 1, which support adjustably near their upper ends 65 a cross-head (not shown). To this cross-head there are adjustably secured a toe post 22 and a heel post 24 which serve to support the shoe against upwardly directed pressure applied on its bottom face. The toe post 22 has a rubber- 70 covered roll 26 thereon for engaging the shoe or last on the top of the forepart, and the heel post is provided with a plate 28 arranged to engage the top face of the heel-end portion of the last, the plate 28 being mounted on a block 30 pivot- 75 ally connected at 32 to the heel post and arranged

to be swung about its pivot by an adjustable screw 34 against the action of a flat spring 36 to adjust the plate 28 so that it will bear evenly on the top face of the last, as more fully disclosed in said Letters Patent No. 1,951,373 referred to above. 5

Mounted on the rods 20 is a slide 38 to which upward and downward movements are imparted through a link 40 connected at 42 to the slide and other mechanism not herein shown in detail 10 since it is fully disclosed in the Letters Patent No. 1,549,243 above mentioned. The slide 38 supports a box 44 provided with a pair of trunnions, one of which is indicated at 46, Fig. 1, mounted in bearings on the slide so that the box may tip about 15 an axis extending laterally of the shoe, the box being held normally in a predetermined position, determined by a spring-pressed plunger 48 carried by the box and engaging the slide, by a spring 50 connecting the slide and the box. 20

Vertically movable in the box 44 is a casting 52 supported by four springs 54 which are yieldable in response to resistance of the shoe to the pressure applied. Mounted in guideways on the casting 52 for movements in directions widthwise of the shoe is a slide 56 which is adjustable along the guideways by means of a screw 58 held against lengthwise movement by a lug 60 fast on the casting. Mounted in guideways on the slide 56 for movements in directions lengthwise of the shoe is 30 a slide 62 (Fig. 3) which is adjustable along the guideways by means of a screw 64 held against lengthwise movement, relative to the slide 62, by a plate 66 fast on the slide 62, the screw being threaded in a lug 68 on the slide 56 and having a 35 hand wheel 70 thereon for turning it. The slide 62 serves as a support for four brackets 72, two of which are located opposite each other near the toe end of the shoe and the other two of which are located opposite each other near the heel end 40 of the shoe. The brackets 72 are connected to corresponding blocks 75, (Fig. 3), which are movable in directions widthwise of the shoe in recesses in the slide 62, in the same manner as in the machine of Letters Patent No. 1,951,373, above 45 referred to, the connections being such as to permit each bracket 72, while movable widthwise of the shoe with its connected block, to swing about a vertical axis. The means for adjusting the blocks and with them the brackets 72 laterally of 50 the shoe is not shown herein in detail since it is fully shown and described in Letters Patent No. 1,951,373 above mentioned. The two blocks mounted near the toe end of the shoe are connected by a shaft 74 which is mounted in bearings on the slide 62 and has right- and left-hand threads thereon engaging the blocks and a hand wheel 76 secured to its outer end for turning it to adjust the blocks toward or from each other. The two blocks near the heel end of the shoe are 60 connected by a shaft 78 (Fig. 1) also mounted in bearings on the slide 62 and provided with right- and left-hand threads engaging the blocks. The shafts 74, 78 are turned simultaneously by the hand wheel 76 through connections including 65 pinions 80, 82 secured respectively to the shafts 74, 78 and engaging a rack bar 84 supported on the slide 62. 75

Connected by parallel links 86, 88 to each of the brackets 72 (Fig. 3) is an angularly shaped holder 90, and each pair of similarly arranged holders serve to support a metal block 92 on which is mounted one of a pair of ironing members or wipers 94, 96. As shown particularly in Figs. 1 and 2, the ironing members 94, 96 extend along the op- 75

posite sides of the shoe between its toe and heel end portions and are shaped both heightwise and widthwise of the shoe to conform substantially to the curvature of the edge of the shoe bottom. The 5 blocks 92 are positioned and secured on the holders 90 by dowel pins 93 which project upwardly into recesses formed in the blocks and by spring controlled plungers 100 which are movably mounted in the holders 90 and are controlled by handles 102 by which they may be withdrawn from recesses formed in the sides of the blocks to permit the blocks to be lifted from the holders. Each 10 of the ironing members 94, 96 has a tongue-and-groove connection 104 with its supporting block 15 90 to maintain it in the proper lateral position and is held in proper lengthwise position by means of a dowel pin 106, Fig. 3, which projects from the block into a recess in the ironing member. As 20 thus mounted, the ironing members 94, 96 may be readily removed simply by lifting them from the blocks 92 when it is desired to substitute different members for use on shoes of widely varying sizes or styles.

Each parallel link 86 has an extension 108, Fig. 23, provided with a slot through which extends a rod 110 pivoted at its lower end to the bracket 72, and encircling this rod is a spring 112 which bears at its lower end against a washer 114 that rests against the extension 108 and at its upper 30 end on a wing nut 116 threaded on the rod. The springs 112 by their actions on the links 86 thus tend to maintain the holders 90 in elevated positions with the outer side faces of the holders against the upwardly extending portions of the 35 brackets 72. It will be understood that the ironing members 94, 96 may be adjusted toward or from each other by means of the hand wheel 76 to accommodate shoes of different sizes, and in order to take care of variations in widths between the foreparts and heel ends of shoes of 40 different sizes the shaft 74 may be and preferably is provided with threads of steeper pitch than the threads on the shaft 78 so that greater movements toward or from each other are imparted to the 45 portions of the ironing members that are nearer the toe end of the shoe than to the portions near the heel end by the same movement of the hand wheel 76. Conveniently also the hand wheel 76 may be provided with a flange 118 which has size 50 indications thereon arranged to cooperate with width indications marked on the adjacent surface of the slide 62 as a guide in adjusting the ironing members. As thus far described the machine herein shown is constructed substantially 55 as disclosed in Letters Patent No. 1,951,373, above-mentioned.

Located opposite each other, one at each end of the shoe, and secured to or formed integral with the slide 62 are a pair of brackets 120, Figs. 1 and 4. Each bracket 120 is provided with an angularly shaped upper portion 122 to which there is connected by pairs of parallel links 124, 126, a similarly shaped holder 128 which serves to support a metal block 130. Each metal block 130 is positioned and secured on its holder 128 by a dowel pin 132 which extends into a recess in the block 130, and mounted on the upper surface of each block 130 is a slide 134.

Each slide 134 is adjustable on its supporting block 130 in directions lengthwise of the shoe by a screw 136 which is held against lengthwise movement relative to the slide 134 by a lug 138 on the slide engaging spaced shoulders on the screw, the screw being threaded into the block 130 and

having a hand wheel 140 thereon for turning it. Each slide 134 carries an upwardly extending pin 142 arranged to be located substantially midway between the opposite sides of the shoe, and pivotally connected to each pin 142 is a pair of end-ironing members or wipers 144, 146, Figs. 4, 5 and 6. The end-ironing members 144, 146 are provided with guideways 148, 150, and slidably mounted in the guideways and pivotally connected respectively at 152, 154 to the side-ironing 10 members 94, 96 are additional ironing members or wipers 156, 158 which extend in directions lengthwise of the shoe along the opposite sides of the ends of the shoe between the side-ironing members 94, 96 and the end members 144, 146. 15

By reference to Fig. 4 it will be seen that the upper surface of the block 130 at the toe end of the shoe is inclined so that the end-ironing members 144, 146 and the ironing members 156, 158 at that end of the shoe are supported at the proper 20 angle to permit them to iron the overlaid margin of the upper around the toe end. Each slide 134 has a cover plate 159, Figs. 2 and 4, which overlies the end-ironing members 144, 146 and the ironing members 156, 158, and each cover plate 25 is cut away as shown to receive an end of the shoe.

One of each pair of parallel links 124, 126, namely the link 124, has an extension 160 provided with a slot through which extends a rod 162 pivoted at its lower end to the upper portion 122 of the bracket 120, and surrounding this rod is a spring 164 which bears at its lower end against a washer 166 resting against the extension 160 and at its upper end against a wing nut 166 threaded 30 on the rod. The springs 164 act through the links 124 to hold the members 128 initially in their uppermost positions with the outer side faces of the holders 128 against the upwardly extending portions 168 of the brackets 120. It will be understood 35 that when the machine is initially at rest the springs 112, 164 act on the links 86, 124 to present all the ironing members in upraised positions. As thus presented the ironing members are arranged to receive and support a previously 40 lasted shoe placed initially thereon bottom downward, and preferably the ironing members are so adjusted relatively to one another that they will engage the overlaid margin of the shoe upper around the entire periphery of the shoe bottom. 45 By reference to Figs. 5 and 6 it will be seen that by rotation of the hand wheels 76, 140 the side members may be adjusted laterally of the shoe and the end members 144, 146 and the members 156, 158 both lengthwise and laterally of the shoe to 50 accommodate shoes of different sizes. When pressure is applied to the bottom of a shoe by the ironing members in the upward movement of the slide 38 after the shoe has been moved into engagement with the members 26, 28, the resistance 55 of the shoe to upward movement of the ironing members causes the parallel links 86, 88 and the parallel links 124, 126 to swing from their initial positions into positions such as indicated in Fig. 4 and thus to move the ironing members 94, 96 and 60 the ironing members 144, 146 bodily inward over the shoe bottom in response to the pressure of the shoe on the members to iron the overlasted margin of the upper along the sides and at the 65 ends of the shoe. 70

As the side-ironing members 94, 96 move inwardly they act to swing the members 156, 158 inwardly and thus to impart to the end members 144, 146 swinging or closing movements laterally of the shoe. Furthermore, by reason of the sliding 75

connections between the end members and the members 156, 158, additional inward swinging movements are imparted to the members 156, 158 about their pivotal connections to the side members as the end members move bodily inward. The members 156, 158 are thus carried bodily inward to iron the marginal portion of the upper along the sides of the ends of the shoe inwardly over the insole by the inward movements of the end and side members. It will be understood that the inward movements of the ironing members are effected against the increasing resistance of the springs 112, 164 through which the ironing members are pressed against the shoe during the ironing operation, so that the pressure of the members on the shoe bottom progressively increases. The swinging of the parallel links is limited by engagement of the holders 99, 128 with their respective brackets 72, 120, after which still greater pressure is applied to the shoe through the springs 54. The holders 99, 128 are positioned initially equal distances above their respective brackets 72, 120, and in order that the different ironing members will be maintained substantially in the same relative heightwise positions at all times the parallel links 124, 126 for connecting the holders 128 to the brackets 120 and the parallel links 86, 88 for connecting the holders 99 to the brackets 72 are of equal lengths. In order to insure that the margin of the upper will be flattened evenly against the insole around the entire bottom of the shoe it is desirable that the different members exert substantially the same amount of pressure on the different portions of the margin of the upper as they move relatively to one another inwardly over the shoe bottom in response to pressure of the shoe upon them. Accordingly the different springs 112, 164 have substantially the same capacity and are preferably so adjusted that they are held under the same initial tension by the wing nuts 116, 166. As the ironing members move inwardly equal movements of compression are imparted to the different springs 112, 164 by the equal links 86, 124, so that the pressure of the different ironing members on the upper is substantially the same at all times.

In order to assist in ironing the overlasted margin of the upper free from wrinkles and setting it in lasted position the illustrated machine is provided with means for maintaining the ironing members in a heated condition. For this purpose the blocks 92, 130 are heated by electrical heating units 170 mounted as shown in recesses in the blocks, and each unit 170 is connected by suitable electrical connections to any convenient source of electrical energy for heating it. From the blocks 92, 130 the heat is conducted to the ironing members mounted upon them.

The illustrated machine is further provided with means which is substantially the same as that shown in Letters Patent No. 1,951,373 above mentioned for preventing return of the side-ironing members 94, 96 to their initial positions in the downward movement of the slide 38 until after the shoe has been substantially released from pressure. This means comprises a latch 174 at each end of the slide 62, Fig. 1, fast on a rock shaft 116 mounted in bearings on the slide. Each latch is arranged to be spring urged inwardly into position to catch on projections 178 on the two holders 99 when the holders have been lowered in the ironing operation far enough to carry these projections below the latch. For moving the latches out of engagement with the projections there is fast on the end of each rock shaft

an arm 180, and pivotally connected to the arms 180 is a rod 182 which extends upwardly and passes loosely through an opening in a block 184 fast to one of the rods 20. The rod 182 has threaded on its upper end a nut 186, the construction being such that when the slide 38 is lowered far enough to carry the shoe away from the shoe-supporting members 26, 28 the nut 186 engages the block 184, after which as the slide continues to move downwardly the latches 174 are swung out of engagement with the projections 178 to permit the holders 99 to swing upwardly and outwardly. For preventing return of the end-ironing members to their initial positions until after the shoe has been substantially released from pressure, there are provided connections between the end and side-ironing means arranged to prevent return of the parts of the end-ironing means to their starting positions until the latches 174 have released the holders 99 to the action of the springs 112. As shown, these connections comprise pins 188 (Fig. 4) carried by the blocks 130 and arranged to extend into slots 190 formed in the blocks 92. It will be understood that the pins 188 extend into the slots 190 to a depth sufficient to permit the blocks 92, 130 to complete their relative movements lengthwise of the shoe without moving the pins out of engagement with the slots 92 and that the slots extend far enough laterally of the shoe to permit the required relative movement of the blocks laterally of the shoe.

The machine herein shown, is further provided with gaging means, substantially like that disclosed in Letters Patent No. 1,951,373 referred to above, to determine the proper lateral position of a shoe on the ironing members. This means comprises gages 192 located at the opposite sides of the forepart of the shoe and other gages 194 located at the opposite sides of the heel end. Each of the forepart gages comprises a metal plate 196 bent into the shape illustrated in Fig. 3 and provided with a covering of soft material such as leather or rubber arranged to contact with the shoe. Each plate is mounted on a block 200 for free turning movement about a vertical axis to permit it to adjust itself to the contour of the shoe and each block 200 is swivelled on the end of a screw 202 which is threaded in an upright supporting arm 204. The two arms 204 are mounted in a guideway extending laterally of the shoe in a plate 205 secured to the slide 62 and are adjustable toward or from each other by a shaft 206 which has right and left threads engaging the respective arms and is provided with a knurled head 208 for turning it. The shaft 206 is held from lengthwise movement by collars 210 which are fast thereon at the opposite sides of a plate 212 secured on the supporting plate 205. The gages 192 are thus adjustable simultaneously toward or from each other by the shaft 206 and are also adjustable each independently of the other by the screws 202 for properly positioning shoes of different sizes and styles. The gages 194 at the heel end of the shoe (Figs. 1 and 2) consist of arms mounted on a block 214 for swinging movements toward or from each other at the opposite sides of the heel end of the shoe and connected by gear teeth 216 to swing in unison, each arm having a leather cover 218 thereon to contact with the shoe. The two arms 194 are adjusted toward and from each other by a shaft 220 having right and left threads in engagement with blocks 222

that are swivelled on the outer ends of the respective arms, the shaft having a knurled head 224 thereon for turning it. The supporting block 214 is pivoted at 226 on a standard 228 which is 5 mounted on the casting 52 so that the arms 194 may be swung out of operative position to facilitate the removal of the ironing members 94, 96. A spring 230 connected to one of the arms 194 and to the standard 228 holds the arms normally 10 in operative position, the arrangement of this spring and its relation to the axis 226 being such that it will also maintain the arms in inoperative position when they are swung to that position.

In order to insure the application of adequate 15 ironing pressure on the upwardly sloping portion of the shoe bottom immediately at the rear of the ball of the shoe by the complementally shaped portions of the ironing members 94, 96 it is contemplated that the roll 26, as illustrated, 20 will be so adjusted as to engage the shoe or last on its upwardly inclined top face at the rear of the toe and thus effect somewhat of a rearward displacement of the shoe as the pressure is applied so as to force it hard against the above- 25 mentioned portions of the ironing members. It will be evident that the plate 28 engaging the top of the heel end and the last does not prevent such rearward movement of the shoe.

Instead of providing the several ironing members with smooth upper-engaging surfaces such as shown in Figs. 2, 5 and 6, it is contemplated 30 that the several members may have serrated upper-engaging faces, so that by their pressure upon the shoe bottom, and especially the final pressure after the completion of their inward movements, they will produce a large number of indentations in the surface of the upper. This will facilitate the roughening of the upper to receive cement if an outsole is to be attached to 35 the shoe by cement, since a roughening tool such as commonly used will act more readily and effectively upon the upraised portions of the upper between the indentations than it would upon an upper having a continuous smooth surface. 40 Portions of ironing members 96' and 158' having such serrated faces are shown in Fig. 9.

In the operation of the machine, briefly summarized, after the ironing members 94, 96 and the ironing members 144, 146 have been adjusted 45 properly for the size of the shoe to be operated upon and have been heated to the desired temperature, the operator places a previously lasted shoe bottom downward on that set of ironing members which is in its lowermost position in the machine 50 and locates the shoe lengthwise in the machine by the complementally shaped ironing members 94, 96, and laterally of the machine by adjustment of the gages 192, 194. While the invention is not limited to use on shoes of the particular kind 55 illustrated, the shoe herein shown is one in which the margin of the upper along the sides and around both the toe and heel ends of the shoe is secured in lasted position by an adhesive and in which an outsole is thereafter cemented to the 60 lasted margin of the upper. Before the shoe is presented to the machine the sides of the shoe may have been lasted by use of the machine of Letters Patent No. 1,943,344 above mentioned, and the ends of the shoe in any suitable well known manner as by use of a bed-lasting machine.

After placing a shoe in position to be operated upon, as above described, the operator then starts the power operation of the machine, whereupon 65 the slide 38 at that side of the machine where

the shoe was placed is elevated and the slide at the other side is lowered. The shoe is accordingly raised until stopped by the abutments 26, 28, and when this occurs the pressure of the bottom of the shoe against the side-ironing members 94, 96 and the end members 144, 146 causes the links 86, 88 and the links 124, 126 to swing from their initially inclined positions, Fig. 3, to positions more nearly horizontal, Fig. 4, as the supporting brackets 72, 128 continue their upward movements, so that the ironing members are forced inwardly over the shoe bottom in wiping engagement with the marginal portion of the upper, the end members 144, 146 being closed inward laterally of the shoe by the action of the side 15 members 94, 96 thereon through the connecting members 156, 158. It will be understood that such movement of the ironing members occurs only after the pressure of the shoe upon them is great enough to overcome the resistance of the 20 springs 112, 164 which are further compressed as the ironing members continue to move inwardly and therefore subject the upper to progressively increasing pressure during the ironing operation. The ironing members as they move 25 inwardly over the insole thus tend to draw the upper around the entire peripheries of the shoe inward over the insole as they apply progressively increasing pressure heightwise of the shoe and heat to the margin of the upper to flatten it 30 against the insole and to eliminate any wrinkles. The inward wiping action of the ironing members is terminated by engagement of the holders 90, 128 with the brackets 72, 120 respectively and thereafter the upper is subjected to further pressure through the springs 54 and the heavy toggle-controlling spring with which machines of this type are provided. In the ironing operation the roll 30 acts on the sloping face of the shoe or 35 last to effect more or less of a rearward displacement of the shoe such as to insure effective pressure on the margin of the upper along that portion of the shoe bottom which slopes rearwardly from the ball of the shoe. The machine comes automatically to a stop with the shoe under pressure and while the shoe is held under pressure the operator presents a shoe to the other half of the machine. As the slide 38 is lowered to release the shoe the latches 174 prevent upward and outward swinging movements of 40 the holders 90 under the influence of the springs 112 until after the shoe has been carried downwardly away from the abutments 26, 28 and thus released from pressure, the holders 128 being also held against upward and outward swinging movements under the influence of the springs 164 45 in advance of the holders 90 by reason of the pin-and-slot connections between the blocks 92, 130. Near the end of the downward movement of the slide 38 the latches are operated to release the holders, thus rendering the springs 112, 164 50 effective to return the ironing members to their starting positions. Since the shoe rests merely by its own weight on the ironing members at that time, there is no danger of any displacement 55 of the margin of the upper by the outward movement of the ironing members.

If the machine is provided with ironing members having serrated upper engaging faces as shown in Fig. 9, a large number of indentations 70 will be formed in the surface of the overlaid marginal portion of the upper as the ironing members are forced with increased pressure against the upper at the completion of their inward movements. The indentations thus pro- 75

duced not only facilitate the roughening of the overlaid margin of the upper, but also serve to indicate clearly that portion of the margin to be roughened preparatory to the laying of the cement-coated outsole thereon.

Fig. 8 shows the bottom of a shoe as it appears after it has been operated upon by the machine when the machine is provided with ironing members having smooth faces. It will be understood that any objectionable wrinkles in the margin of the upper are eliminated as the upper is ironed inwardly and pressed smoothly against the insole along the sides and around the ends of the shoe. The shoe is thus provided with a bottom surface best fitted for the reception of its outsole.

It is to be understood that the invention is not limited to a machine that irons the margin of the upper at both the toe and heel ends of a shoe nor that operates along both the forepart and the shank portions of the shoe bottom; and that it is also not limited to use on shoes the uppers of which are fastened in lasted position by an adhesive.

Having described the invention, what I claim as new and desire to secure by Letters Patent of the United States is:

1. In a machine for ironing the bottoms of shoes after lasting, heated ironing means constructed and arranged to engage initially, in locations between the toe and heel-end portions of a shoe and also around an end of the shoe, the marginal portion of the upper previously laid inwardly over an insole substantially in lasted position, and means for moving said ironing means inwardly over the shoe bottom lengthwise and laterally of the shoe to iron the overlasted margin of the upper while applying substantial pressure to said margin heightwise of the shoe.

2. In a machine for ironing the bottoms of shoes after lasting, ironing means constructed and arranged to engage initially, in locations between the toe and heel-end portions of a shoe and also around both ends of the shoe, the marginal portion of the upper previously laid inwardly over an insole substantially in lasted position, means for heating said ironing means, and means for moving said ironing means inwardly over the shoe bottom while applying pressure to the upper heightwise of the shoe to smooth its margin free from wrinkles.

3. In a machine for ironing the bottoms of shoes after lasting, heated ironing means arranged to extend along the sides of a shoe in locations between its toe and heel-end portions and around an end of the shoe and constructed to engage initially the marginal portion of an upper previously laid inwardly over an insole substantially in lasted position, and means constructed and arranged to move said ironing means inwardly over the shoe bottom lengthwise and laterally of the shoe and during said movement progressively to increase the pressure of said means on the upper heightwise of the shoe to smooth the overlasted margin of the upper free from wrinkles.

4. In a machine for ironing the bottoms of shoes after lasting, heated ironing means constructed and arranged to engage initially the overlaid marginal portion of an upper along the sides of a shoe in locations between its toe and heel-end portions and around an end of the shoe, means for moving said ironing means inwardly over the shoe bottom in wiping engagement with the upper, and springs arranged to act through said last-named means progressively to increase

the pressure of said ironing means on the upper during its inward movement.

5. In a machine for ironing the bottoms of shoes after lasting, ironing means comprising a plurality of relatively movable heated members constructed and arranged to extend along the sides of a shoe in locations between its toe and heel-end portions and around an end of the shoe and to engage initially the marginal portion of the upper previously laid inwardly over an insole substantially in lasted position, and mechanism for effecting relative movements of said members to cause them to iron the margin of the upper inwardly over the shoe bottom with substantial pressure directed heightwise of the shoe.

6. In a machine for ironing the bottoms of shoes after lasting, ironing means comprising a plurality of ironing members arranged to extend along the sides of a shoe in locations between its toe and heel-end portions and around an end of the shoe and to engage initially the overlaid marginal portion of the upper, means for heating said members, and means for effecting relative movement of the shoe and said members heightwise of the shoe to apply pressure to the upper and for also moving said members relatively to one another inwardly over the shoe bottom to iron the upper.

7. In a machine for ironing the bottoms of shoes after lasting, ironing means comprising a plurality of ironing members arranged to extend along the sides of a shoe in locations between its toe and heel-end portions and around an end of the shoe and to engage initially the overlaid marginal portion of the upper, and automatic mechanism for moving said members relatively to one another inwardly over the shoe bottom to iron the upper and for applying increased pressure to the upper heightwise of the shoe through said members after they have completed their inward movements.

8. In a machine for ironing the bottoms of shoes after lasting, ironing means constructed and arranged to engage initially the marginal portion of an upper previously laid inwardly over an insole substantially in lasted position, said ironing means comprising end members movable lengthwise of the shoe and relatively movable laterally of the shoe to iron the upper around an end of the shoe bottom and also side members movable laterally of the shoe to iron the upper along the sides of the shoe bottom in locations beyond said end members, and means for heating said end and side members.

9. In a machine for ironing the bottoms of shoes after lasting, ironing means constructed and arranged to engage initially the marginal portion of an upper previously laid inwardly over an insole substantially in lasted position, said ironing means comprising end members movable lengthwise of the shoe and relatively movable laterally of the shoe to iron the upper around both the toe and heel ends of the shoe bottom and also side members movable laterally of the shoe to iron the upper along the ball-and-shank portions of the shoe bottom, and means for heating said end and side members.

10. In a machine for ironing the bottoms of shoes after lasting, ironing means constructed and arranged to engage initially the marginal portion of an upper previously laid inwardly over an insole substantially in lasted position, said ironing means comprising end members movable lengthwise of the shoe and relatively movable laterally of the shoe to iron the upper around

- an end of the shoe bottom and also side members movable laterally of the shoe to iron the upper along the sides of the shoe bottom in locations beyond said end members, means for moving said end members lengthwise of the shoe and the side members laterally of the shoe, means for moving the end members laterally of the shoe by the movements of the side members, and means for heating said end and side members.
11. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, connections for swinging the end members by the movements of the side members, and means for heating said end and side members.
12. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, devices in sliding engagement with which said end members are movable lengthwise of the shoe, means for operating said devices by the movements of the side members to impart to the end members their swinging movements, and means for heating said end and side members.
13. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, devices pivotally connected to the side members and slidably connected to the end members for swinging the end members by the movements of the side members while permitting the movements of the end members lengthwise of the shoe, and means for heating said end and side members.
14. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, additional ironing members arranged to iron the upper in intervals between said end and side members and also to impart to the end members their swinging movements by the movements of the side members, and means for heating all said members.
15. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, additional ironing members arranged to iron the upper in intervals between said end and side members and along which the end members are movable lengthwise of the shoe, means for operating said additional members to swing the end members laterally of the shoe by the movements of the side members, and means for heating all said members.
16. In a machine for ironing the bottoms of shoes after lasting, ironing means constructed and arranged to engage initially the marginal portion of an upper previously laid inwardly over an insole substantially in lasted position, said ironing means comprising end-ironing members movable lengthwise of the shoe and each mounted to swing also laterally of the shoe, side-ironing members movable laterally of the shoe in locations beyond said end members, additional ironing members arranged to iron the upper in intervals between said end and side members, said additional members being pivotally connected to the side members and slidably connected to the end members for imparting to the end members their swinging movements by the movements of the side members, and means for heating all said members.
17. In a machine for ironing the bottoms of shoes after lasting, ironing members arranged to support a shoe placed thereon bottom downward and constructed to engage the overlaid marginal portion of the upper along the sides of the shoe between the toe and heel-end portions of the shoe and around an end of the shoe, said members being movable inwardly over the shoe bottom in wiping engagement with the upper in response to pressure of the shoe upon them, and means for heating said members.
18. In a machine for ironing the bottoms of shoes after lasting, heated ironing means constructed and arranged to engage initially, in locations between the toe and heel-end portions of a shoe and around an end of the shoe, the marginal portion of the upper extending inwardly over an insole substantially in lasted position, said means being movable inwardly over the shoe bottom to iron the overlasted margin of the upper in response to pressure of the shoe thereon.
19. In a machine for ironing the bottoms of shoes after lasting, ironing means arranged to support a shoe placed initially thereon bottom downward and constructed to engage the marginal portion of the upper on the shoe bottom in locations between the toe and heel-end portions of the shoe and around an end of the shoe, said means being mounted for movement inwardly over the bottom of the shoe to iron the margin of the upper, and means for heating said ironing means.
20. In a machine for ironing the bottoms of shoes after lasting, ironing means arranged to support a shoe placed thereon bottom downward and constructed to engage the overlaid marginal portion of the upper along the sides of the shoe between its toe and heel-end portions and around the toe and heel ends of the shoe, means for operating said ironing means to wipe the overlaid margin of the upper in directions inwardly from the edge of the insole while applying progressive-

ly increasing pressure heightwise of the shoe to smooth said margin free from wrinkles, and means for heating said ironing means.

21. In a machine for ironing the bottoms of 5 shoes, ironing means arranged to support a shoe placed initially thereon bottom downward and constructed to engage the marginal portion of the upper extending inwardly over the shoe bottom, said ironing means comprising end members movable lengthwise of the shoe and relatively movable laterally of the shoe to iron the upper around an end of the shoe bottom and side members movable laterally of the shoe to iron the 10 upper along the sides of the shoe bottom in locations beyond said end members.

22. In a machine for ironing the bottoms of 15 shoes, ironing means arranged to support a shoe placed initially thereon bottom downward and 20 constructed to engage the marginal portion of the upper extending inwardly over the shoe bottom, said ironing means comprising end-ironing members movable lengthwise of the shoe and each mounted to swing also laterally of the shoe, 25 side-ironing members movable laterally of the shoe in locations beyond said end members, and means for swinging the end members by the movements of the side members.

23. In a machine for ironing the bottoms of 30 shoes after lasting, ironing members arranged to support a shoe placed thereon bottom downward and constructed to engage the overlaid marginal portion of the upper along the sides of the shoe between its toe and heel-end portions and around 35 an end of the shoe, and parallel links arranged to move said members inwardly over the shoe bottom in response to pressure of the shoe upon them.

24. In a machine for ironing the bottoms of 40 shoes after lasting, ironing members arranged to extend along the sides of a shoe in locations between its toe and heel-end portions and around an end of the shoe and constructed to engage initially the overlaid marginal portion of the upper 45 on the shoe bottom, means for supporting said members, said supporting means and the shoe being relatively movable in directions heightwise of the shoe, and mechanism for moving said members inwardly over the shoe bottom in response to such relative movement.

25. In a machine for ironing the bottoms of 50 shoes after lasting, ironing members arranged to engage initially the marginal portion of an upper on the bottom of a shoe in locations between the toe and heel-end portions of the shoe and around an end of the shoe, means for supporting said members, means for moving said supporting means relatively to the shoe in a direction heightwise of the shoe, and connections between said 55 supporting means and said members for moving them inwardly over the shoe bottom in response to such movement of the supporting means.

26. In a machine for ironing the bottoms of 60 shoes after lasting, a plurality of members arranged to engage initially, in locations between the toe and heel-end portions of a shoe and around an end of the shoe, the marginal portion of the upper previously laid inwardly over an insole, means for supporting said members 65 movable relatively to the shoe in a direction heightwise of the shoe, connections between said members and their supporting means for moving said members inwardly over the shoe bottom in response to such movement of the supporting 70 means, and spring means for yieldingly opposing 75

the inward movements of said members while pressing them upon the shoe bottom.

27. In a machine for ironing the bottoms of 5 shoes, ironing means arranged to engage initially, in locations between the toe and heel-end portions of a shoe and around an end of the shoe, the marginal portion of the upper previously laid inwardly over an insole in lasted position, said means comprising a plurality of members relatively movable lengthwise and laterally of the 10 shoe in directions inwardly over the shoe bottom to iron the overlasted margin of the upper in response to pressure of the shoe upon them.

28. In a machine for ironing the bottoms of 15 shoes after lasting, heated members for ironing 20 the marginal portion of an upper on the bottom of a shoe in locations along the sides of the shoe between its toe and heel-end portions and around both ends of the shoe, said members being mounted for movements inwardly over the shoe bottom 25 in wiping engagement with the upper in response to pressure of the shoe upon them.

29. In a machine for ironing the bottoms of 30 shoes after lasting, heated members for wiping the overlasted margin of an upper in directions 25 inwardly over an insole in locations along the sides of a shoe between its toe and heel-end portions and around an end of the shoe, and means 35 for imparting to said members their inward movements in response to pressure of the shoe upon them.

30. In a machine for ironing the bottoms of 40 shoes after lasting, heated ironing means constructed and arranged to engage initially the 35 marginal portion of an upper extending inwardly over an insole substantially in lasted position and comprising members relatively movable to iron the upper around an end of the shoe bottom, and mechanism for imparting to said members their relative movements in response to pressure of the shoe on said ironing means.

31. In a machine for ironing the bottoms of 45 shoes after lasting, heated ironing means constructed and arranged to engage initially the marginal portion of an upper extending inwardly over an insole substantially in lasted position and comprising members movable lengthwise of the shoe and relatively movable laterally of the shoe to iron the upper around an end of the shoe bottom, and mechanism for imparting to 50 said members their movement lengthwise of the shoe and their relative movement laterally of the shoe in response to pressure of the shoe on said ironing means.

32. In a machine for ironing the bottoms of 55 shoes after lasting, heated ironing means constructed and arranged to engage initially the marginal portion of an upper extending inwardly over an insole substantially in lasted position, said ironing means comprising end members movable 60 lengthwise of the shoe and relatively movable laterally of the shoe to iron the upper around an end of the shoe bottom and also side members movable laterally of the shoe to iron the upper along the sides of the shoe bottom in locations 65 beyond said end members, and means for moving said end members lengthwise of the shoe and the side members laterally of the shoe in response to pressure of the shoe on said end and side members, the end members being movable 70 laterally of the shoe in response to the movements of the side members.

33. In a machine for ironing the bottoms of 75 shoes after lasting, heated ironing means constructed and arranged to engage initially the

5 marginal portion of an upper extending inwardly over an insole substantially in lasted position, said ironing means comprising end members movable lengthwise of the shoe and relatively movable laterally of the shoe to iron the upper around an end of the shoe bottom and also side members movable laterally of the shoe to iron the upper along the sides of the shoe bottom in locations beyond said end members, means for
 10 moving said end members lengthwise of the shoe and the side members laterally of the shoe in response to pressure of the shoe on said end and side members, and devices connecting said end and side members for moving the end members laterally of the shoe by the movements of the side members.

34. In a machine for ironing the bottoms of shoes after lasting, heated ironing means constructed and arranged to engage initially the marginal portion of an upper extending inwardly over an insole substantially in lasted position, said ironing means comprising end-ironing members movable lengthwise of the shoe and each mounted to swing also laterally of the shoe, side-ironing members movable laterally of the shoe in locations beyond said end members, means for moving said end members lengthwise of the shoe and the side members laterally of the shoe in response to pressure of the shoe on said end and side members, devices in sliding engagement with which said end members are movable lengthwise of the shoe, and means for operating said devices by the movements of the side members to impart to the end members their swinging movements.

35. In a machine for ironing the bottoms of shoes after lasting, heated ironing means constructed and arranged to engage initially the marginal portion of an upper extending inwardly over an insole substantially in lasted position, said ironing means comprising end-ironing members movable lengthwise of the shoe and each mounted to swing also laterally of the shoe, side-ironing members movable laterally of the shoe in locations beyond said end members, means for moving said end members lengthwise of the shoe and the side members laterally of the shoe in response to pressure of the shoe on said end and side members, and additional ironing members arranged to iron the upper in intervals between said end and side members and to impart to the end members their swinging movements by the movements of the side members.

36. In a machine for ironing the bottoms of shoes after lasting, heated ironing means constructed and arranged to engage initially the marginal portion of an upper extending inwardly over an insole substantially in lasted position, said ironing means comprising end members movable lengthwise of the shoe and relatively movable laterally of the shoe to iron the upper around an end of the shoe bottom and also side members movable laterally of the shoe to iron the upper along the sides of the shoe bottom in locations beyond said end members, swinging links for imparting to said end members movement lengthwise of the shoe and to the side members movements laterally of the shoe in response to pressure of the shoe on said end and side members, and means for moving the end members laterally of the shoe by the movements of the side members.

37. In a machine for ironing the bottoms of shoes after lasting, heated ironing means constructed and arranged to engage initially the

5 marginal portion of an upper extending inwardly over an insole substantially in lasted position, said ironing means comprising end members movable lengthwise of the shoe and relatively movable laterally of the shoe to iron the upper around an end of the shoe bottom and also side members movable laterally of the shoe to iron the upper along the sides of the shoe bottom in locations beyond said end members, swinging links for imparting to said end members movement lengthwise of the shoe and to the side members movements laterally of the shoe in response to pressure of the shoe on said end and side members, and devices connecting said end and side members for moving the end members laterally of the shoe by the movements of the side members.

38. In a machine for ironing the bottoms of shoes after lasting, ironing members movable lengthwise and laterally of a shoe and arranged to engage the marginal portion of an upper extending inwardly over an insole substantially in lasted position around the toe end of the shoe bottom, other ironing members movable laterally of the shoe in similar engagement with the marginal portion of the upper along the ball portion of the shoe, means for moving all of said members inwardly over the shoe bottom in response to pressure of the shoe upon them, and means for heating said members.

39. In a machine for ironing the bottoms of shoes, end-ironing means and side-ironing means movable inwardly over the bottom of a shoe in response to pressure of the shoe thereon, means for preventing outward return movement of said side-ironing means until after the shoe has been released substantially from the pressure applied, and means arranged to permit said end-ironing means to move outwardly only with said side-ironing means.

40. In a machine for ironing the bottoms of shoes, end-ironing means and side-ironing means movable relatively to each other inwardly over the bottom of a shoe in response to pressure of the shoe thereon, separate spring means associated with each of said end and side-ironing means for yieldingly opposing their inward movements and for thereafter moving them outwardly, means for holding said side-ironing means against outward movement until after the shoe has been released substantially from the pressure applied, and means for preventing outward movement of the end-ironing means in advance of the side-ironing means.

41. In a machine for ironing the bottoms of shoes, end members movable lengthwise of the shoe for ironing the marginal portion of an upper around an end of the bottom of the shoe, side members movable laterally of the shoe for ironing the marginal portion of the upper along the sides of the bottom of the shoe in locations beyond said end members, said end and side members being mounted for movements inwardly over the shoe bottom in response to pressure of the shoe upon them, spring means for yieldingly opposing the inward movements of said end and side members and for thereafter moving them outwardly, mechanism for holding the side members against outward movement, means to cause said mechanism to release the side members after the shoe has been released substantially from the pressure applied, and connections between said end and side-ironing members for prevent-

ing outward movement of the end members until the side members begin their outward movements.

42. In a machine for ironing the bottoms of shoes, end members movable lengthwise and laterally of the shoe for ironing the marginal portion of an upper around an end of the bottom of the shoe, side members movable laterally of the shoe for ironing the marginal portion of the upper along the sides of the shoe bottom in locations beyond said end members, mechanism for moving said end and side members inwardly over the bottom of the shoe in response to pressure of the shoe upon them, spring means for yielding oppositely the inward movements of said end and side members and for thereafter moving them outwardly, means for preventing outward movement of the side members until after the shoe has been released substantially from the pressure applied, and pin-and-slot connections between the end and side members arranged to permit outward movement of the end members only during the outward movement of the side members.
43. In a machine for ironing the bottoms of shoes, ironing means comprising members arranged to support a shoe placed thereon bottom downward and constructed to engage the overlusted margin of the upper along the sides of the shoe between its toe and heel-end portions and around an end of the shoe, means for relatively adjusting said members to accommodate shoes of different sizes, and means for moving said members inwardly over the shoe bottom to iron the overlusted margin of the upper.
44. In a machine for ironing the bottoms of shoes, means for ironing the marginal portion of an upper inwardly over an insole at the opposite sides of a shoe between its toe and heel-end portions and around an end of the shoe comprising end and side members movable inwardly over the shoe bottom in response to pressure of the shoe upon them, and means for adjusting the side members laterally of the shoe and for adjusting the end members lengthwise and laterally of the shoe to accommodate shoes of different sizes.
45. In a machine for ironing the bottoms of shoes, means for ironing the marginal portion of an upper previously laid inwardly over an insole along the sides and around an end of the bottom of a shoe comprising side members arranged to extend along the opposite sides of the shoe between its toe and heel-end portions and end members arranged to extend around an end of the shoe, said end members comprising a pair of members located at the extreme end of the shoe and pivotally connected for swinging movements laterally of the shoe about an axis extending heightwise of the shoe and members slidingly connected to said pivoted members and having their forward ends pivotally connected to said side members, and means for adjusting said side members laterally of the shoe and for adjusting said end members lengthwise and laterally of the shoe to accommodate shoes of different sizes.
46. In a machine for ironing the bottoms of shoes after lasting, ironing means for engaging initially the marginal portion of an upper previously laid inwardly over the bottom of a shoe, said ironing means having a serrated upper-engaging face, and means for effecting relative movement of said ironing means and the shoe laterally of the shoe to iron the margin of the upper and then heightwise of the shoe to produce

indentations in the surface of the upper through the action of said serrated face on the upper.

47. In a machine for ironing the bottoms of shoes after lasting, ironing means for engaging initially the marginal portion of an upper previously laid inwardly over the bottom of a shoe, said ironing means having a serrated upper-engaging face, and means for moving said ironing means inwardly over the bottom of the shoe in engagement with the margin of the upper and for thereafter increasing the pressure of the ironing means on the upper to produce indentations in the surface of the upper through the action of said serrated face on the upper.

48. In a machine for ironing the bottoms of shoes after lasting, heated ironing members for engaging the marginal portion of an upper overlying an insole, said members having serrated upper-engaging faces, and means for moving said members inwardly over the shoe bottom to iron the overlusted margin of the upper and for applying pressure to the upper heightwise of the shoe through said members to produce indentations in the surface of the upper.

49. In a machine for operating on shoes, wiping means for engaging initially the marginal portion of an upper previously laid inwardly over the shoe bottom, said wiping means being movable relatively to the shoe to wipe the upper and having a serrated upper-engaging face, and means for applying pressure to the shoe through said wiping means at the completion of the wiping operation to produce indentations in the surface of the upper through the action of said serrated face on the upper.

50. That improvement in methods of making shoes which consists in applying pressure to the marginal portion of an upper on the bottom of a shoe substantially all around the forepart and along the sides of the shank portion of the shoe at one operation, and in the pressing operation producing indentations in the surface of the upper to facilitate roughening of the upper preparatory to the attachment of an outsole to the shoe by cement.

51. That improvement in methods of making shoes which consists in engaging the upper initially with a serrated ironing member after the upper has been already laid inwardly over the insole and moving said member inwardly over the shoe bottom in wiping contact with the upper, and thereafter increasing the pressure of said member on the upper to produce indentations in the surface of the upper by the action of the serrations on the upper.

52. That improvement in methods of making shoes which consists in applying pressure in the presence of heat to the marginal portion of an upper previously laid inwardly over an insole and fastened to the insole, and in the pressing operation producing indentations in the surface of the upper to facilitate roughening of the upper preparatory to the attachment of an outsole to the shoe by cement.

53. That improvement in methods of making shoes which consists in ironing the marginal portion of an upper on the bottom of a shoe with a heated member having a serrated upper-engaging face, and through pressure of said member on the upper producing indentations in the surface of the upper.

54. In a machine for operating on shoes, wipers movable relatively to one another and arranged to extend along the sides and around an end of the bottom of a shoe, supporting means for said

wipers movable relatively to the shoe in a direction heightwise of the shoe, and connections between said wipers and their supporting means for moving the wipers inwardly over the shoe 5 bottom in response to such movement of the supporting means.

55. In a machine for operating on shoes, wipers for wiping the margin of an upper at the opposite sides of the bottom of a shoe, wipers for wiping the margin of the upper around an end 10 of the shoe, said end wipers being mounted for swinging movements each about an axis extending heightwise of the shoe, means for moving said end and side wipers bodily inward over the 15 shoe bottom, and additional wipers extending along the opposite sides of the end of the shoe and arranged to be moved inwardly over the shoe bottom in wiping engagement with the upper in response to the movement of the side wipers.

56. In a machine for operating on shoes, side wipers arranged to extend along the opposite sides of the forepart and shank portions of a shoe, end wipers located at an end of the shoe and mounted for swinging movements laterally of the shoe 20 each about an axis substantially midway between the opposite sides of the shoe, means for imparting to said end wipers and said side wipers bodily movements inwardly over the shoe bottom in wiping engagement with the margin of the upper, 25 and additional wipers extending in directions lengthwise of the shoe between said end and side wipers and arranged to be moved inwardly over the shoe bottom by the inward movements of said end and side wipers to wipe the margin of the 30 upper along the opposite sides of the end of the shoe.

57. In a machine for operating on shoes, a pair of side wipers arranged to extend along the opposite sides of a shoe, a pair of end wipers located at an end of the shoe and mounted for swinging movements laterally of the shoe each about an axis extending heightwise of the shoe, means for moving said end and side wipers inwardly over the shoe bottom in wiping engagement with the margin of the upper, and additional wipers slidably mounted on said end wipers 40 and arranged to extend along the opposite sides of the end of the shoe, said additional wipers being connected to said side wipers for movements therewith inwardly over the shoe bottom to cause 45 them to wipe the upper and also to impart to said end wipers closing movements laterally of the shoe.

58. In a machine for operating on shoes, means movable inwardly over the bottom of a shoe in wiping engagement with the marginal portion of the upper, said means comprising end wipers movable lengthwise of the shoe and each mounted to swing also laterally of the shoe, side wipers 50 movable laterally of the shoe in locations beyond said end wipers, and members pivotally connected to said side wipers and slidably connected to said end wipers for imparting to the end wipers their movements laterally of the shoe by the movements of the side wipers.

59. In a machine for operating on shoes, means movable inwardly over the bottom of a shoe in wiping engagement with the marginal portion of the upper, said means comprising end wipers 60 movable lengthwise of the shoe and each mounted to swing also laterally of the shoe, side wipers movable laterally of the shoe in locations beyond said end wipers, and members in sliding engagement with which the end wipers are movable 65 lengthwise of the shoe, said members being ar-

ranged to impart to the end wipers their movements laterally of the shoe by the movements of the side wipers.

60. In a machine for operating on shoes, means movable inwardly over the bottom of a shoe in wiping engagement with the marginal portion of the upper, said means comprising end wipers movable lengthwise of the shoe and each mounted to swing also laterally of the shoe, side wipers 5 movable laterally of the shoe in locations beyond 10 said end wipers, and additional wipers arranged to act on the shoe in intervals between said end and side wipers, said additional wipers being connected to the end wipers for swinging the latter laterally of the shoe in response to the movements of the side wipers. 15

61. In a machine for operating on shoes, means movable inwardly over the bottom of a shoe in wiping engagement with the marginal portion of the upper, said means comprising end wipers 20 movable lengthwise of the shoe and each mounted to swing also laterally of the shoe, side wipers movable laterally of the shoe in locations beyond 25 said end wipers, and additional wipers arranged to act on the shoe in intervals between said end and side wipers, said additional wipers being slidably connected to the end wipers to permit the end wipers to move relatively to them lengthwise of the shoe and being pivotally connected to the side wipers for imparting to the end wipers 30 their movements laterally of the shoe in response to the movements of the side wipers.

62. In a machine for operating on shoes, wipers for wiping the marginal portion of an upper at the opposite sides and around an end of the bottom of a shoe, and mechanism for moving said wipers inwardly over the shoe bottom in response to pressure of the shoe upon them. 35

63. In a machine for operating on shoes, end and side wipers movable relatively to one another 40 and arranged to extend respectively around an end and along the sides of the bottom of a shoe, and means for moving said end wipers lengthwise 45 of the shoe and the side wipers laterally of the shoe in response to pressure of the shoe upon them.

64. In a machine for operating on shoes, wipers for wiping the marginal portion of an upper at the opposite sides of the bottom of a shoe, other wipers for wiping the marginal portion of the upper around the toe end of the shoe, and parallel links for moving all said wipers inwardly over the shoe bottom in response to pressure of the shoe upon them. 50

65. In a machine for operating on shoes, wiping means movable inwardly over the bottom of a shoe in wiping engagement with the marginal portion of the upper, said wiping means including end wipers movable lengthwise of the shoe and movable also toward each other laterally of the shoe, and means for imparting to said end wipers 55 their movements lengthwise and laterally of the shoe in response to pressure of the shoe on said wiping means.

66. In a machine for operating on shoes, end wipers movable lengthwise and laterally of a shoe in wiping engagement with the marginal portion of the upper around an end of the shoe bottom, side wipers movable laterally of the shoe 60 in wiping engagement with the marginal portion of the upper in locations beyond said end wipers, means for imparting to said end and side wipers their movements lengthwise and laterally of the shoe respectively in response to pressure of the shoe upon them, and means for imparting to said 65

end wipers their movements laterally of the shoe by the movements of the side wipers.

67. In a machine for operating on shoes, end wipers movable lengthwise and laterally of a 5 shoe in wiping engagement with the marginal portion of the upper around an end of the shoe bottom, side wipers movable laterally of the shoe in wiping engagement with the marginal portion of the upper in locations beyond said 10 end wipers, means for imparting to said end and side wipers their movements lengthwise and laterally of the shoe respectively in response to pressure of the shoe upon them, members in sliding engagement with which said end wipers 15 are movable lengthwise of the shoe, and means for operating said members by the movements of the side wipers to impart to the end wipers their movements laterally of the shoe.
68. In a machine for operating on shoes, end 20 wipers movable lengthwise of a shoe and mounted for swinging movements also laterally of the shoe in wiping engagement with the marginal portion of the upper around an end of the shoe bottom, side wipers movable laterally of the 25 shoe in wiping engagement with the marginal portion of the upper in locations beyond said end wipers, means for moving said end and side wipers lengthwise and laterally of the shoe respectively in response to pressure of the shoe 30 upon them, and members slidably connected to said end wipers and pivotally connected to the side wipers for imparting to the end wipers their movements laterally of the shoe by the movements of the side wipers.
69. In a machine for operating on shoes, end 35 wipers movable lengthwise of a shoe and mounted for swinging movements also laterally of the shoe in wiping engagement with the marginal portion of the upper around an end of the shoe bottom, side wipers movable laterally of the 40 shoe in wiping engagement with the marginal portion of the upper in locations beyond said end wipers, means for moving said end and side wipers lengthwise and laterally of the shoe 45 respectively in response to pressure of the shoe upon them, and additional wipers arranged to act on the upper in intervals between said end and side wipers and to impart to the end wipers their swinging movements by the movements of the side wipers.

70. In a machine for operating on shoes, end 50 wipers movable lengthwise of a shoe and mounted for swinging movements also laterally of the shoe in wiping engagement with the marginal portion of the upper around an end of the shoe bottom, side wipers movable laterally of the 55

shoe in wiping engagement with the marginal portion of the upper in locations beyond said end wipers, swinging links arranged to impart to said end and side wipers their movements lengthwise and laterally of the shoe respectively in response to pressure of the shoe upon said wipers, and means for imparting to said end wipers their movements laterally of the shoe by the movements of the side wipers. 5

71. In a machine for operating on shoes, end 10 wipers movable lengthwise of a shoe and mounted for swinging movements also laterally of the shoe in wiping engagement with the marginal portion of the upper around an end of the shoe bottom, side wipers movable laterally of the 15 shoe in wiping engagement with the marginal portion of the upper in locations beyond said end wipers, swinging links arranged to impart to said end and side wipers their movements lengthwise and laterally of the shoe respectively in response to pressure of the shoe upon said wipers, and additional wipers arranged to 20 act on the upper in intervals between said end and side wipers and along which the end wipers are movable lengthwise of the shoe, said additional wipers being arranged to impart to the end wipers their movements laterally of the shoe by the movements of the side wipers. 25

72. In a machine for ironing the bottoms of 30 shoes after lasting, heated ironing means constructed and arranged to engage initially, around an end of a shoe, the marginal portion of the upper extending inwardly over an insole substantially in lasted position, said ironing means comprising members movable inward 35 lengthwise and laterally of the shoe to subject the margin of the upper around the end of the shoe to an inward wipe while applying heat thereto, and spring means tending to hold said members against inward movement and against 40 the resistance of which they are thus movable.

73. In a machine for ironing the bottoms of 45 shoes after lasting, ironing means constructed and arranged to engage initially, around an end of a shoe, the marginal portion of the upper extending inwardly over an insole substantially in lasted position, said ironing means comprising heated members mounted to swing toward each other about an axis extending heightwise of the shoe to subject the upper to 50 an inward wipe while applying heat thereto, and spring means tending to swing said members apart and against the resistance of which they are thus movable toward each other.

CHARLES F. PYM.
